UNITED STATES PATENT OFFICE.

CONRAD SCHROEDER, OF MILWAUKEE, WISCONSIN.

DESIGN FOR A CORK-RETAINING DEVICE.

SPECIFICATION forming part of Design No. 31,311, dated August 1, 1899.

Application filed June 14, 1899. Serial No. 720,566. Term of patent 14 years.

To all whom it may concern:

Be it known that I, CONRAD SCHROEDER, a citizen of the United States, residing at Milwaukee, in the county of Milwaukee and State 5 of Wisconsin, have invented and produced a new and original Design for Cork-Retaining Devices; and I do hereby declare the following to be a full, clear, and exact description of the same, reference being had to the accompanying drawings, forming a part thereof.

In the said drawings, Figure 1 is a vertical sectional view on the line 1 1 of Fig. 2, and Fig. 2 is a plan view of a cork-retaining device embodying my new design.

15 My design relates to the new and original shape of the article.

The leading or essential feature consists in the unitary design for a cork-retaining device made the subject of illustration, comprising 20 the shape of the outer slightly-flaring annu-

lar wall A, with a lower annular series of ribs a a a, separated by concavities or depressions b b b, and the flattened annular top portion B and central top depressed portion C.

Minor features of this design comprise the 25 tapered or inwardly-flaring annular wall c of the said central top depressed portion C and the rounded outer annular edge d of the flattened annular top portion B.

Having thus described my invention, what 30 I claim as new, and desire to secure by Letters Patent, is—

The design for a cork-retaining device substantially as herein shown and described.

In testimony whereof I affix my signature 35 in presence of two witnesses.

CONRAD SCHROEDER.
